FIG. 1 is a perspective view of a disc player combined with radio receiver and tape recorder showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken line showing on FIGS. 1-7 is for illustrative purposes only and forms no part of claimed design.
